FOREIGN PATENT DOCUMENTS

WO WO-2011128854 A2 * 10/2011 ..... B02C 13/1835

Primary Examiner — Garth Rademaker*Assistant Examiner* — Fitzgerald L Butac(74) *Attorney, Agent, or Firm* — Todd R. Fronek; Larkin Hoffman Daly & Lindgren, Ltd.(57) **CLAIM**

The ornamental design for a vertical shaft impact crusher crushing chamber, as shown and described.

DESCRIPTION

FIG. 1 is a perspective view of a vertical shaft impact crusher crushing chamber showing our new design;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof; and,

FIG. 7 is a bottom plan view thereof.

The broken lines shown in the drawings illustrate portions of the vertical shaft impact crusher crushing chamber that form no part of the claimed design.
